RAZOR BLADE MAGAZINE

Sidney H. Benjamin, Milwaukee, Wis.

Application June 5, 1941, Serial No. 396,683

4 Claims. (Cl. 30—40)

My invention relates to safety blade magazines and refers particularly to safety blade magazines carrying a plurality of stacked safety razor blades and means adapted to remove a safety razor blade deposited upon a safety razor head element.

Safety razors have been so constructed that a safety razor blade magazine holder, carrying a removable safety blade magazine containing a plurality of stacked safety razor blades, may be inserted between a safety razor blade deposited upon a safety razor head element and the head element, the movement of said magazine holder and its blade magazine removing said deposited blade from its said position and depositing an unused blade upon said razor head, the withdrawal of said magazine holder and its blade magazine from contact with said razor head withdrawing said formerly deposited blade from contact with said razor head.

My invention relates to safety blade magazines carrying means adapted to accomplish the removal of a deposited blade from a safety razor head by co-operation with safety razor blade magazine holders.

In the removal of such deposited blades, it is essential that the removing means have some element whereby the blade will become removably attached to the removing device while the blade is still within, or upon, the razor head, such attachment being of a character whereby the withdrawal of the withdrawing means from the razor head will carry the blade with it.

The attaching means between the blade and the removing device may be a part of the magazine holder or a part of the blade magazine carried by the magazine holder, and my invention is directed to blade magazines in which such attaching means are carried by the blade magazine.

The construction, operation and advantages of the razor magazine holder of my invention will be evident upon a consideration of my specification and the accompanying drawings, in which similar parts are designated by similar numerals.

Figure 1 is a top plan view of a safety razor blade magazine of my invention.

Figure 2 is a section through the line 2—2 of Figure 1.

Figure 3 is a section through the line 3—3 of Figure 1.

Figure 4 is a top plan view of one form of a safety blade magazine holder adapted for use with the safety blade magazine of Figures 1, 2, and 3.

Figure 5 is a section through the line 5—5 of Figure 4.

Figure 6 is a rear end view of the device of Figure 4.

Figure 7 is a top plan view of the combined devices of Figures 1 to 6 inclusive.

Figure 8 is a section through the line 8—8 of Figure 7.

Figure 9 is a section through the line 9—9 of Figure 7.

Figure 10 is a top plan view of a modified form of a safety razor blade magazine of my invention.

Figure 11 is a rear end view of Figure 10.

Figure 12 is a side view of Figure 11, partly broken away.

Figure 13 is a top plan view of a modified form of a magazine holder adapted for use with the blade magazine of Figures 10, 11, and 12.

Figure 14 is an enlarged section through the line 14—14 of Figure 13.

Figure 15 is an enlarged rear end view of the device of Figure 13.

Figure 16 is a top plan view of the combined devices of Figures 10 to 15 inclusive.

Figure 17 is an enlarged section through the line 17—17 of Figure 16.

Figure 18 is a section through the line 18—18 of Figure 17.

The particular form of a blade magazine of my invention illustrated in Figures 1, 2, and 3 comprises a top member 40; two side members 41, 41, extending above the top member 40, the two spaced bottom members 42, 42 forming an opening, or recess, 43, and the end members 44 and 45, the end member 44 being extended downwardly to form the longitudinal opening 46, through which the bottom blade 100 may be withdrawn, or ejected, while the remaining blades 100, 100 are retained within the magazine.

A plurality of blades 100, 100 are positioned within the magazine, and are pressed downwardly by the spring 47 fastened to the top 40 by means of the rivet 48. The top member 40 carries the two downwardly extended lugs 49, 49 adapted to pass through an opening, or openings, in the razor blade 100, 100 and through openings in the spring 47. The upper portion of the lugs 49, 49 is extended above the top 40 forming the two blade engaging members 50, 50, the rearward portions of which are undercut, as shown particularly in Figure 2, so positioned that they will enter the openings in a used blade positioned 55 upon a razor, when the device is positioned be-

neath said blade. The top 40 has also a recess 51, adapted to receive a lug or a razor head.

My razor blade magazines are of such construction as to allow of their use with magazine holders, and to cooperate with razor heads to withdraw a previously deposited blade and to deposit an unused blade and position it thereon for shaving purposes.

In order to withdraw a used blade it is necessary that some means be employed whereby the used blade may be removably attached to the magazine holder, or to the blade magazine, while the devices are in contact with the razor head and that the attaching means be of such construction as to withdraw the used blade from the razor head.

My invention is directed to razor blade magazines adapted to be used with blade magazine holders, in which such withdrawing means are a part of the blade magazine, as will be clearly shown upon a consideration of the description of my devices.

In order to show the novelty and usefulness of the blade magazines of my invention, I illustrate modified forms of blade magazine holders adaptable for use therewith.

One form of a safety razor blade magazine holder adapted to operate with my razor blade magazine, shown particularly in Figures 4, 5, and 6 adapted for the Gem type of razor, comprises a top member formed of the two members 20 and 20' having a connecting bridge 21, thus forming the recess 22 in this top member. The rear portion of the top member is extended upwardly into a U-shaped member 23, having elongated openings 23' therein, these openings 23' being connected with two recesses 31 and 31' in the top members 20 and 20' respectively. The number of these recesses in the top members 20 and 20' varying to correspond with the number of blade engaging members of the particular blade magazine employed. The forward portions of the top members 20 and 20' are extended downwardly forming the blade guiding members 24 and 24' respectively, the ends of the blade guiding members 24 and 24' being bevelled as shown.

The top member carries the two sides comprising the U-shaped members 25 and 25', which are extended downwardly 26 and 26', thence inwardly and outwardly forming the two loop members 27 and 27', forming a runway, thence downwardly 28 and 28' and thence inwardly forming the two spaced bottom members 29 and 29' forming a runway and forming an opening 30, between the two side members 29 and 29'. These two members 29 and 29' may be substituted by a single bottom member with a recess in its forward end portion. One of the sides has a Z-shaped resilient retaining member 32, the central portion of which is inwardly positioned within the side member, thus forming a blocking member therein, this blocking member being capable of removal from its normal blocking position by movement of its outwardly extended member 32'.

In operation, the blade magazine is introduced into the holder through its rearward end and moved forwardly therein until the two elements are in the position shown in Figures 7, 8, and 9. During this inward movement, the blade engaging members 50, 50 pass through the openings 23' and the recesses 31, 31' and when the magazine is in proper position within the holder, the inner portion of the Z-shaped retaining member 32 is in the position shown particularly in Figure

7, thus preventing the outward movement of the magazine.

It is evident that a blade magazine without extended blade engaging members, such as 50, 50, cannot be employed to withdraw a blade from a razor head and that a magazine holder cannot be employed with a blade magazine having such blade engaging members unless it has rear recesses such as 31, 31'.

To operate the thus combined magazine holder and blade magazine, the two outward extended arms 52, 52' of the blade guiding members 24 and 24' respectively are introduced between the guard of a razor head and a blade positioned thereon, and moved inwardly, during which movement the positioned blade is removed from lugs positioning it on the guard and moves upwardly over the upper face of the members 24 and 24' and then across the upper faces 20 and 20' of the magazine holder, this movement continuing until the blade engaging members 50, 50 become inserted through openings in blade. When the blade is in this position, the magazine holder with the blade magazine is withdrawn from contact with the razor head, thus withdrawing the formerly positioned blade from the razor.

The device of my invention shown in Figures 10 to 18, inclusive, is adapted for use with the Gillette type of razor and is similar to that previously shown and described, similar parts being designated by similar numerals.

This form of razor blade magazine, however, varies slightly from that described in order to adapt it to the particular construction of the Gillette type of razor and blades, but such variations do not affect the co-ordination between the magazine holder and a blade magazine, nor do they affect the operation of these two assembled elements for a withdrawal of a positioned blade from a razor head, and hence, a detailed description is not necessary for a clear understanding of their construction and application.

As the means for withdrawing the bottom blade from the stacked blades within the blade magazine and positioning it upon the razor guard is not a part of this application, the details thereof are not herein described.

It will thus be seen that the devices of my invention are blade magazines adapted to be removably received by a blade magazine holder carrying blade removing means, whereby the insertion of, and withdrawal from, a razor head having a blade deposited thereon, will withdraw said blade from said razor head, said blade withdrawal means being a part of my blade magazine.

By "blade magazine" I mean a magazine containing a plurality of stacked razor blades, so constructed as to allow of the ejection of a single blade at one time.

By "operative position" and similar words I mean that the blade magazine is so positioned within the magazine holder as to allow of the ejection of a single blade therefrom by the ejection means employed with the magazine holder.

I do not limit myself to the particular size, shape, number, or arrangement of parts as shown and described, as these are given solely for the purpose of clearly describing my invention.

What I claim is:

1. A safety razor blade magazine adapted for the reception of a plurality of stacked blades comprising a casing having a top member, two spaced bottom members, two side members connecting said top members and said bottom mem-

bers, an end member enclosing said casing and an end member positioned at right angles to said top member and said bottom member forming a space between said last mentioned end member and said spaced bottom members and allowing the passage of a single razor blade from within said casing, a plurality of blade positioning lugs within said casing adapted to pass through openings in all of a stack of blades except the lowest one positioned within said casing, resilient means carried by said top member adapted to move said blade stack toward said bottom members, and means extending outwardly from said casing adapted to be inserted within razor blade openings.

2. A safety razor blade magazine adapted for the reception of a plurality of stacked blades comprising a casing having a top member, two spaced bottom members, two side members connecting said top members and said bottom members, an end member enclosing said casing and an end member positioned at right angles to said top member and said bottom member forming a space between said last mentioned end member and said spaced bottom members and allowing the passage of a single razor blade from within said casing, a plurality of blade positioning lugs within said casing adapted to pass through openings in all of a stack of blades except the lowest one positioned within said casing, resilient means carried by said top member adapted to move said blade stack toward said bottom members, and means extending outwardly from said casing adapted to be inserted within an opening of a razor blade.

3. A safety razor blade magazine adapted for the reception of a plurality of stacked blades comprising a casing having a top member, two spaced bottom members, two side members connecting

5 and extending above said top members and said bottom members, an end member enclosing said casing and an end member positioned at right angles to said top member and said bottom member forming a space between said last mentioned end member and said spaced bottom members and allowing the passage of a single razor blade from within said casing, a plurality of blade positioning lugs within said casing adapted to pass through openings in all of a stack of blades except the lowest one positioned within said casing, resilient means carried by said top member adapted to move said blade stack toward said bottom members, and means extending outwardly from said casing adapted to be inserted within razor blade openings.

4. A safety razor blade magazine adapted for the reception of a plurality of stacked blades comprising a casing having a top member, two spaced bottom members, two side members connecting and extending above said top members and said bottom members, an end member enclosing said casing and an end member positioned at right angles to said top member and said bottom member forming a space between said last mentioned end member and said spaced bottom members and allowing the passage of a single razor blade from within said casing, a plurality of blade positioning lugs within said casing adapted to pass through openings in all of a stack of blades except the lowest one positioned within said casing, resilient means carried by said top member adapted to move said blade stack toward said bottom members, and an end portion of each said lug extending outwardly from said casing adapted to be inserted within an opening of a razor blade.

SIDNEY H. BENJAMIN.
